FIG. 1

FIG. 2

FIG. 3

FIG. 4

FIG. 5

FIG. 6

By his Attorney
Inventor
Benjamin H. Marcus
Mauroe Block

UNITED STATES PATENT OFFICE.

BENJAMIN H. MARCUS, OF BROOKLYN, NEW YORK.

BELT BUCKLE.

Application filed May 17, 1928. Serial No. 278,409.

This invention relates to improvements in belt buckles and has for one of its objects the provision of a belt buckle in combination with a purse.

Another object of the invention is to provide a belt buckle having a purse and a belt gripping member hingedly mounted thereon, and a hinge pin upon which the purse is mounted adapted to exert a tension on the belt gripping member to maintain the belt in adjusted position about the waist of the wearer.

A further object of the invention is to provide a belt holding member in which the belt may be splicingly maintained.

Another object of the invention is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purposes of illustration, is shown in the accompanying drawings, in which,

Figure 1 is a front view in elevation of my improved buckle attached to a belt;

Fig. 2 is a perspective view of the buckle showing the purse in open position;

Fig. 3 is a rear or bottom view of the buckle;

Fig. 4 is a sectional view on line 4—4, Fig. 1;

Fig. 5 is a fragmental sectional view taken on line 5—5, Fig. 1, showing how the purse is hinged, and

Figs. 6 and 7 are detail views of the belt holding member.

Referring now to the drawings in detail 10 indicates the base or body portion of the buckle provided with a centrally located depression or recess 11 adapted to receive 60 therein a purse 12 preferably formed of a single strip of sheet metal, and comprises an outer shell or cover 13, an extension or wall 14 bent inwardly of the sheet 13 to form a change compartment 15. A portion 65 is struck up from the wall 14 and bent outwardly to form a hinge 16, through which passes a hinge pin 17 which terminates at one end thereof in a spring end 18. The body 10 is provided with a depression 19 to 70 accommodate the hinge 16 on the purse 12. To maintain the purse in closed position on the buckle, there is provided a member 20 which is slidably arranged on the bottom wall 21 of the recess 11 and maintained 75 thereon by lugs 22 struck up from the said wall 21. The said member 20 is provided at one end thereof with a latch portion 23 which in normal closed position engages a depression 24 in the shell 13, and is maintained 80 in said closed position by a spring 25 secured thereto and in engagement with the inner surface of a depending side wall 26 on the body portion 10 of the buckle.

At one end of the body portion 10 there 85 is hingedly mounted the usual toothed belt securing member 30 which engages one end of a belt 31 and secures same to the buckle. At the opposite end of the buckle there is likewise pivotally mounted a belt 90 gripping member 32 which is normally pressed against the locking end 33 of a belt holding member 34 by the spring end 18 of the hinge pin 17. The locking end 33 of the belt holding member is provided with a 95 turned-over end 35 against which the belt gripping member 32 abuts, to prevent loosening of the belt around the waist of the wearer. The belt 31 is secured to the belt holding member 34 by threading or 100 splicing same through slots 36 in the said member as shown in dot and dash lines in Fig. 7 of the drawings. The belt is further secured to the holding member 34 by bent-over lugs 37 and 38 on the said holding member.

The belt may be made in various sizes and adjusted around the body by inserting the

belt holding member 34 between the top wall of the buckle body 10 and the belt gripping member 32 so that the turned-over end 35 engages the end of the said gripping member. To loosen or unhook the belt, all that is necessary is to press upwardly against the tension of the spring 18, a finger piece 39 on the belt gripping member and the turned-over end 35 will come out of engagement with the end of the belt gripping member.

To open the purse, the end 20^a of the latch member 20 is pressed against the tension of the spring 25 and the latch end 23 will come out of engagement with the depression 24, and the purse will snap open slightly from which position it may be fully opened.

From the above it will be seen that I have provided a belt buckle adapted to be readily adjusted around or removed from the waist of the wearer, the said buckle being provided with a purse which is normally tightly closed and which may be readily opened when desired.

Having described my invention, what I claim as new and desire to secure by Letters Patent, is:

1. In a purse adapted to be attached to a belt, a base, a cover, a hinge pin upon which the cover is mounted associated with the base, a belt gripping member pivotally mounted on the base, and a spring end integral with the hinge pin exerting a tension on the gripping member to grip the belt.

2. In a purse adapted to be attached to a belt, a base, a cover, a hinge pin upon which the cover is mounted associated with the base, a belt gripping member pivotally

mounted on the base, a spring end integral with the hinge pin exerting a tension on the gripping member to grip the belt, and a spring pressed latch on the base in operative engagement with the cover for the purpose specified.

3. In a purse adapted to be attached to a belt, a base, a cover, a hinge pin upon which the cover is mounted associated with the base, a belt gripping member pivotally mounted on the base, a spring end integral with the hinge pin exerting a tension on the gripping member to grip the belt, and a spring pressed latch slidably mounted on the base in operative engagement with the cover for the purpose specified.

4. In a device of the nature described adapted to be attached to a belt, a base, a depression in the base, a purse forming cover hingedly mounted on the base and adapted to fit into the depression slideways on the bottom wall of the base, a latch member slidably mounted in the said slideways in operative engagement with the cover and a spring on the latch member to maintain the cover in closed position.

5. In a device of the nature described adapted to be attached to a belt, a base, a purse forming member pivotally mounted on the base, a belt securing member at one end of the base, a belt gripping member pivotally mounted at the opposite end of the base, a spring forming one end of the purse member pivot exerting a tension on the belt gripping member, and a belt holding member adapted to be gripped by the gripping member to maintain the belt in position.

BENJAMIN H. MARCUS.
